UNITED STATES PATENT OFFICE

1,968,719

FIRE DOOR

Samuel P. Smurr, Oak Park, Ill., assignor, by
mesne assignments, to Majestic Rolling Door
Company, Chicago, Ill., a corporation of Illinois

Original application October 22, 1927, Serial No.
227,876, now Patent No. 1,843,633, dated Fe-
bruary 2, 1932. Divided and this application
April 7, 1930, Serial No. 442,273. Renewed De-
cember 22, 1933.

9 Claims. (Cl. 189—56)

My invention relates to fire doors of the rolling shutter type, and has for its object improvements in devices of that kind.

The present invention is a division of my pend-
ing application Serial No. 227,876, filed October 22,
1927, and has to do particularly with the spool
upon which the curtain is wound.

A fire curtain is composed of metallic slats
which are pivotally connected to each other.
10 These slats are provided with end locks to pre-
vent the slats from slipping longitudinally with
respect to each other. These end locks are sepa-
rate pieces riveted to the slats and are thicker
than the slats to which they are connected. When
15 a curtain is wound upon a barrel, the end locks
pile upon each other. In this piling operation,
there is a tendency for each successive end lock,
when it comes upon one below it, to shift or slip
endwise on the barrel and carry the curtain with
20 it. This tendency increases with repeated coil-
ings of the curtain on the barrel.

When the curtain is guided by the supporting
brackets, as is the ordinary practice, this shifting
25 of the curtain causes the outer layers on the bar-
rel to come into frictional contact with the inner
face of one or the other of the brackets, and
friction of the moving curtain on the stationary
30 bracket tends to interfere with the free move-
ment of the curtain. The principal object of the
present invention is to put the curtain guides on
the barrel and thus avoid the friction mentioned.

In the accompanying drawings
35 Fig. 1 is an end elevation of the complete de-
vice secured to a wall and with the curtain or shut-
ter rolled up;

Fig. 2 is a front elevation partly broken away;

Fig. 3 is a central longitudinal section of the
operating parts, but with the curtain removed;

Fig. 4 is a front elevation of the curtain sup-
40 porting spool detached, together with one slat of
the curtain resting on the spool;

Fig. 5 is a transverse section of the spool at an
enlarged scale and showing the first or top slat
of the curtain connected thereto; and

Fig. 6 is an elevation of Fig. 5.

Secured to the wall 11 at each side of the door-
way are certain angle irons 12 which furnish guide
slots for the edges of the curtain, and secured to
the upper ends of these angle irons are brackets
50 13 which support the working apparatus. On the
brackets 13 is a hood 14 which encloses the parts
between the brackets.

Supported in roller bearings 13a in the brackets
is a curtain-carrying spool composed of gears 15,
55 a barrel 16 and curtain-holding collars 17. The

barrel is secured to the inner hubs of the gears
by the screws 18, and the entire spool is support-
ed by the outer hubs of said gears resting in the
bearings 13a of the brackets 13.

Supported to turn in the hub of the left hand
gear 15 is a shaft 19, one end of which extends
beyond the bearing to the left, and the other end
of which terminates inside of the barrel short of
the hub of the gear 15 at the right. Secured to the
inner end of the shaft 19 is a collar 20, the pur-
pose of which is to retain the shaft centrally in
the barrel when one turns with respect to the
other.

Secured to the shaft 19 adjacent to the collar 20
is another collar 21. A spring 22 has one end
secured to the collar 21 and the other end secured
to the hub 23 of the left hand gear 15. A spacing
tube 24 surrounds the shaft 19 and is located be-
tween the collar 21 and the hub 23. Its purpose
is to stretch the spring 22 so that its coils will not
be in contact with each other. It will be evident
that the spring 22 may be wound or unwound by
holding the barrel stationary and turning the
shaft, or by holding the shaft stationary and
turning the barrel.

Secured to the outer end of the shaft 19 is an
index plate 25 having a long hub 26, the outer
surface of which is threaded. On the outer edge
of the plate 25 are bosses 26a which are drilled,
tapped and countersunk. In one of these bosses
is a screw 27, but the bosses are all alike so that
the screw 27 may be inserted in any one of
them.

Pivoted at 28 on the left hand bracket 13 is
a lever 29, provided with a weight and connec-
tions to a chain having a fusible link therein, as
is ordinarily the case with automatic rolling shut-
ters. The lever 29 is provided with means for
engaging any one bosses 26 as is set forth in my
previous application, the details of which are
not necessary to an understanding of the present
invention.

Mounted upon the threaded hub of the index
plate 25 is a gear 37 having the interior of its
hub threaded to match the threads on the hub
100 of the index plate. It will be evident that when
either the gear 37 or the index plate is turned
with respect to the other, the gear 37 will travel
axially inward or outward according to the direc-
tion in which the turning occurs.

On the upper part of the left hand bracket
13 is a boss which serves as a bearing for a short
shaft 40, on the ends of which are secured pin-
ions 41 and 42 which engage gears 15 and
37. The gears and pinions are of different sizes.

so that when gears 15 and 37 are both moving, gear 15 has a less angular velocity than does gear 37.

The collars 17 are made in halves and are clamped to the barrel 16 by bolts 43. This is so that these collars can be put on or removed from the barrel 16 after it has been secured to the gears. The collars form the direct means for securing the curtain to the barrel.

10 The two halves of a collar, when secured in position, have their outer surfaces forming a spiral, the step of which is at the middle of one-half as shown in Fig. 5. At the point where this step occurs is a boss 44 for receiving a screw 45, and on each side of this boss are notches 46 and 47 for receiving the flanges of a channel 48. The curtain is made of a series of similar slats hinged together, the upper slat of which is shown at 49 in Figs. 5 and 6. The parts are so arranged 15 that the bend which forms part of the hinge connecting one slat to another, in the first slat of the curtain, fits into the space between the boss 44 and notch 47, and is held in place by the channel 48 serving as a clamp actuated by the screw 45. 20 25 Slat bearing rings with spiral contour have been used before, but I do not know of such rings being made in the form of collars which can be put upon or removed from a barrel when that barrel is supported in its bearings. Also, heretofore, the top slat has been secured to the rings 30 by screws passing thru holes drilled in the slat and tapped in the ring. Such construction is not interchangeable. By clamping the collars in any convenient position in line on the barrel, and 35 clamping the first slat of the curtain to the collars, the curtain may be adjusted longitudinally on the barrel without the drilling of holes. Also, there is simplification in erection and repairs.

Referring to Fig. 4, it will be seen that the slats 40 of the curtain rest upon the edges of the collars 17 as shown at 56. The end flanges of the spool are formed by the gears 15 which have their inner faces slightly beveled as shown in Figs. 3 and 4. This bevel corresponds to the bevel on 45 the flanges of a spool used for thread, but is very much less in extent. The length of the slats which form the curtain is a little less than the distance between the gear flanges 15, and these flanges serve as guides to prevent the edges of 50 the curtain rubbing against stationary guides or the inside faces of the brackets when being raised or lowered. In automatically operated curtains of the kind here involved, it is important to avoid stationary lateral guides for the edges of 55 the curtain, as the friction caused by lateral strain may prevent the curtain from falling in case of a fire.

When the spring is wound, the parts are locked by the use of the lever 29 and the chain with a 60 fusible link. In this condition, the connection between the shaft 19 and the barrel is by way of the index plate, and gears 27, 42 and 41 to the gear teeth on the left hand flange 15. When a fire occurs, the lever 29 releases the index plate, 65 and the spring 22 acts thru the gears to move the

curtain downward in the manner described in my previously mentioned application.

What I claim is:

1. In a device of the class described, a curtain-carrying spool consisting of a barrel, flanges secured to the ends of the barrel, and spiral curtain supporting collars mounted upon the barrel and providing means for clamping the upper terminal slat of a curtain. 80

2. In a device of the class described, a curtain-carrying spool consisting of a barrel, beveled flanges secured to the ends of the barrel, one of which flanges serves as a means for driving it, curtain supporting collars formed in halves and clamped to the barrel between the flanges thereof, and curtain-clamping means associated with said collars and serving to clamp and hold the upper terminal slat of a curtain. 85 90

3. In a device of the class described, a barrel upon which a curtain may be wound, flanges secured to the barrel and turning therewith, said flanges serving to guide the edges of the curtain while said curtain is being wound and unwound, and means for turning said barrel by the application of power to one of the flanges thereof. 95

4. In a device of the class described, a spool consisting of a barrel and a pair of gears having hubs extending into the barrel and secured thereto and externally projecting hubs serving as journals to support the barrel in bearings. 100

5. In a device of the class described, a spool consisting of a barrel and a pair of interiorly tapered flanges secured thereto, said flanges having exteriorly projecting hubs serving as journals to support the barrel in bearings and one of said flanges provided with means for driving said spool. 110

6. The combination with a pair of brackets furnishing bearings, of a curtain-carrying barrel supported to turn in said bearings, said barrel 115 being provided with curtain guiding flanges secured to and turning with the barrel, and a driving connection supported in one of said brackets and serving to convey power from outside of the brackets to one of said flanges. 120

7. A barrel, a plurality of collars mounted upon said barrel, said collars having their exteriors in the form of equal spirals about the axis of the barrel as a center, and a bar extending across the collars at the terminals of the spirals, said bar serving to secure the terminal part of a curtain to the collars. 125

8. A barrel, a plurality of collars mounted upon the barrel, said collars having alined notches in their exterior surfaces, and a bar secured to said collars at their notches, said bar serving to clamp the terminal part of a curtain to said collars. 130

9. A barrel, a plurality of collars formed in halves and clamped upon the barrel, said collars having alined recesses in their exterior surfaces, 135 and a bar located in said recesses and secured to said collars, said bar serving to secure the terminal part of a curtain to said collars.

SAMUEL P. SMURR. 140
